SEALING DEVICE

Carlo Corizzo, Newburgh, N. Y.

Application March 15, 1938, Serial No. 196,046

3 Claims. (Cl. 20—69)

My invention relates to sealing devices and more particularly to sealing devices for use in connection with sashes and sash frames.

One of the principal objects of my invention is to provide a sealing device fashioned in a manner to permit free movement of a window sash within a frame while at the same time effectively sealing the sash relative to the frame to prevent the entrance of air between the relatively sliding portions thereof.

Another object of my invention is to provide a device of the above described character capable of easy attachment to window constructions already in use without modifying the same.

A further object of my invention is to provide a window sealing device which, while simple in construction, durable in use and efficient in operation, is so constructed and arranged to permit the free adjustment of the sashes relative to the frame.

Other objects and advantages will be apparent from the following description, appended claims and annexed drawing.

Referring to the drawing wherein like reference characters designate like parts throughout the several views:

Figure 1 is an interior elevation of a window construction illustrating my invention applied thereto.

Figure 2 is an exterior elevation of the window construction illustrated in Figure 1 with my invention applied thereto.

Figures 3 and 4 are detail sectional views taken on the lines 3—3 and 4—4 of Figure 1 respectively.

In practicing my invention I provide a window frame 5 having top, side and bottom frame elements, 6, 7 and 8 respectively, each formed with sash receiving channels 9. Upper and lower sashes 10 and 11 are positioned within the frame, each having top and bottom rails 12 and 13 respectively and connecting side rails 14 slidably in the channels 9. Said rails are provided with outer and inner faces 15 and 16 respectively. The top rail 12 of the upper sash 10 and the bottom rail 13 of the lower sash 11 are seated within the channels 9 of the top and bottom frame elements respectively when the sashes are in closed position as illustrated in Figures 1 and 2 of the drawing.

The lower rail 13 of the upper sash 10 and the upper rail 12 of the lower sash 11 are each provided with lower faces 17 and the inner faces 16 thereof are adjacent each other when the sashes are in closed position.

A strip 18 of pliable material, for instance felt, is secured to each of the outer faces 15 of the side rails of both of the sashes and to the outer faces of the upper and lower rails 12 and 13 of the upper and lower sashes respectively. Each strip is fashioned with right angularly disposed sections 19 and 20. The section 20 of each strip engages the adjacent frame element of the frame for sliding engagement therewith.

Elongated members 21, for instance metal strips, are fashioned with right angularly disposed sections 22 and 23 overlying the respective sections 19 and 20 of the strips and conceal the latter from view. A rectangular-shaped strip 24 of pliable material, for instance felt, is secured to the lower face 17 of the lower rail 13 of the upper sash 10 and engages the inner face 16 of the upper rail 12 of the lower sash 11 and a similar shaped member 25, for instance a metal strip, overlies the strip 24 and likewise conceals the same from view.

The sections 19 of the strips 18, sections 22 of the members 21, strips 24 and members 25 are secured to the respective rail faces by means of fastening devices or screws 26 for movement therewith and relative to the frame elements. The members 21 and 25 are fashioned with right angularly disposed end sections 27 embracing the exposed ends of the respective strips and maintain the strips in a compact contactual or gasketed condition relative to the frame and rails, thereby effecting a seal between the frame and sashes when the sashes are in closed position and preclude creeping or expansion of the strips without the members due to relative movement of the sashes and the frame.

From the foregoing it will be apparent that the members effectively conceal the felt strips from view and that the end sections of the respective members coact therewith to maintain the strips in a gasketed condition relative to the rails and frame for preventing the passage of air from one side of the sashes to the other when the sashes are in closed position relative to each other and the window frame.

What I claim is:

1. A device of the character described, comprising, in combination, a window frame fashioned with opposed sash receiving channels, a sash having sash rails slidable in said channels, strips of pliable material mounted on said rails and having offset sections engaging said frame, members covering the entire outer faces of said strips, and screws securing said members and said strips to said rails in a manner to permit rela-

tive movement between said sections and said frame, said members each fashioned with oppositely disposed end sections spaced from said frame and said sash and partially embracing exposed end faces of said strips for concealing the same from view and maintaining the strips in gasketed condition relative to said frame and rail whereby to effect a seal therebetween and to preclude creeping of said strips without said members upon movement of said sash within said frame.

2. A device of the character described, comprising, in combination, a window frame fashioned with opposed sash receiving channels, a sash having sash rails slidable in said channels, strips of pliable material appressingly mounted on said rails and having right angularly disposed sections appressingly engaging said frame, members having right angularly disposed portions and covering the entire outer faces of said strips, means securing said members and said strips to said rails in a manner to permit relative movement between said sections and said frame, said members each fashioned with oppositely and right angularly disposed end portions spaced from said frame and said sash and partially embracing the exposed end faces of said strips for maintain-

ing the strips in a compact contactual condition relative to the frame and rails whereby to effect a seal between the frame and sash when in closed position and to preclude creeping of the strips without said members due to relative movement of said sash and said frame. 5

3. In a window construction, the combination of a window frame fashioned with opposed frame members having sash receiving channels, a sash having rail members slidable in said channels, strips of pliable material engaging said frame and rail members, retaining elements covering the outer faces of said strips, and means securing one of said elements and one of said strips to one of said members adjacent each of said channels and in a manner to permit relative movement between said sash and said frame, said elements fashioned with end sections spaced from said frame and rail members and partially embracing exposed end faces of said strips for concealing the same from view and maintaining the strips in gasketed condition relative to said frame and rail members whereby to effect a seal therebetween and to preclude creeping of said strips without said elements by movement of said sash within 20 25 said frame.

CARLO CORIZZO.
